(57) **CLAIM**

The ornamental design for an electric drying machine for laundry purpose, as shown and described.

DESCRIPTION

FIG. 1 is a front perspective view of the electric drying machine for laundry purpose showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view showing the state that the door has been closed.

The broken lines depict portions of the electric drying machine for laundry purpose that form no part of the claimed design.

1 Claim, 8 Drawing Sheets
